UNITED STATES PATENT OFFICE.

OSCAR L. SMITH, OF GRAND RAPIDS, MICHIGAN.

DISPLAY DEVICE.

1,115,604.

Specification of Letters Patent.

Patented Nov. 3, 1914.

Application filed June 6, 1911. Serial No. 631,587.

To all whom it may concern:

Be it known that I, OSCAR L. SMITH, a citizen of the United States, residing at Grand Rapids, in the county of Kent and 5 State of Michigan, have invented an Improvement in Display Devices, of which the following description, in connection with the accompanying drawings, is a specification, like letters on the drawings representing 10 like parts.

The invention to be hereinafter described relates to display devices for use in stores and other places for the exhibition of merchandise.

15 In devices of this character it is desirable to provide a rack for supporting the goods and to so sustain the rack that it may be rotated horizontally to present successive portions for inspection or examination of 20 the goods sustained by it. In order to protect the goods the rack should be so related to a show case that when not in use the rack may be bodily moved into the case and when 25 it is desirable to examine the goods sustained by it, the rack may be bodily moved to the front of the case, in which position it may be rotated, as described.

The aims and purposes of this invention are to provide a display device of the above 30 general character, all as will hereinafter more fully appear in connection with the accompanying drawings, illustrating one form of the invention, which in its true scope is defined by the claims.

35 In the drawings: Figure 1 is a side view, parts being shown in section, of a display device embodying the present invention; Fig. 2 is a plan view, showing the rack bodily moved to its inner position with respect to the case; Fig. 3 is an enlarged detail, showing the mounting of the rack supporting arms; and Fig. 4 is a section on line 4—4, Fig. 3.

The show case indicated by dotted lines 45 in Figs. 1 and 2 may be of any approved form or character adapted to inclose or contain the rack, and in the present instance is shown as formed of a base 1 and glass sides, back, and top, with appropriate doors, 50 if desired, for closing the front.

Secured to the case, preferably on the base 1, is a plate 2 having a portion 3 provided with a socket 4 to receive the pintle or stud 5 of a turn-table or rotatable support 6, said

turn-table or support 6 being preferably 55 seated in a socket formed in the plate 2, as indicated in Fig. 4, the construction being such that the turn-table or support 6 may be rotated. Above the turn-table or support 6 and separated from it by the spacing 60 blocks 7 is a cap 8, said cap and spacing blocks being secured to the turn-table or support 6 by appropriate means, such as the screw bolts 9, 9, Fig. 3.

To restrain too free rotative movement 65 of the turn-table, the latter is provided with diametrically opposed sockets 10, Fig. 3, adapted to be engaged by a spring pressed plunger 11, the spring 12 whereof normally acts to impel the plunger in a direction to 70 engage said sockets and to impress the end of the plunger against the circular periphery of the turn-table. The end of the plunger or the walls of the sockets 10 may be made rounding or curved, to the end that 75 while they will coact to restrain rotative movement of the turn-table under ordinary conditions of use, they will permit such rotative movement in response to force. While this is the preferred construction, the invention is not necessarily limited thereto, 80 but includes also such a device or equivalent which may require positive disengagement, as by withdrawing the plunger.

85 Mounted on separate pivots 13 and 14 carried by the turn-table or support 6 are the rack supporting arms 15 and 16, the adjacent end portions of which extend between the cap 8 and the turn-table, as indicated in Fig. 3, and are provided with intermeshing segment racks 17 and 18, the construction being such that while the rack supporting arms may turn individually on their separate pivotal supports carried by the turn-table, yet their movements will be 90 concurrent, as will be apparent, by reason of the intermeshing racks. One of said rack supporting arms is provided with a pin 20 which projects into a slot 19 formed in the cap 8 of the turn-table, whereby said rack 95 arms are limited in their swinging movements about their individual pivots 13 and 14. Rising from each of the rack supporting arms 15 and 16 are the uprights 21, 22, Fig. 1, having pivotally connected thereto 100 the transversely extending arms 23 and 24 which carry the rack, comprising any suitable means for sustaining the goods, such,

for instance, as the rods 27 and 28, which are pivotally mounted on the ends of said transverse arms 23 and 24.

From the construction thus far described, it will be obvious, that when the rack is positioned within the case, if power be applied thereto in the direction of the arrow, Fig. 2, the rack may be bodily moved toward the front of the case, the rack supporting arms at such times turning individually but concurrently on their separate pivots 13 and 14; and reversely, when the rack is in its outer position, if a force be applied thereto in a direction opposite the arrow, Fig. 2, the rack may be bodily moved into the case. When the rack is bodily moved toward the front of the case in the manner stated, it is desirable to lock the rack supporting arms in alinement, in which position the rack may be turned about its vertical axis to present different portions thereof and the goods sustained thereby into position for convenient inspection and examination; and similarly, when the rack is bodily moved to its inner position and the rack supporting arms take position as indicated by Fig. 2, it is desirable to lock them in such position. To this end the invention contemplates means, one form of which is shown by the drawings, and consists of the following.

Mounted on the segment portion or inner end portion of one of the rack supporting arms, as 15, is a spring pin or plunger 29, Fig. 4, the spring of which normally acts to project the plunger or pin and cause its rounded end to engage one of a series of three sockets 30 formed in the surface of the turn-table or support 6, Figs. 3 and 4.

From the construction described it will be noted that the rack may be moved to and from a position within the case and when in either position will be locked or held by the spring plunger 29; and also that when the rack is moved to its outer position with the rack supporting arms in alinement as indicated by Fig. 3, the rack may be rotated. Preferably the holding force of the spring plunger or pin 29 carried by the rack arm is made greater than the holding force of the spring plunger 11 which acts upon the turn-table, with the result, that when the rack has been moved into its outer position, Fig. 2, by a pull centrally thereof, to bring the rack supporting arms into alinement and the plunger or pin 29 has engaged the central recess 30 of the series, a pull or push upon one of the end portions of the rack will cause rotative movement thereof without disturbing the relation of the rack supporting arms.

What is claimed is:—

1. In a display device, the combination of a case or cabinet, a turn-table pivotally mounted for rotative movement in said case

or cabinet, rack supporting arms separately pivoted to said turn-table at opposite sides respectively of the pivotal axis of said turn-table and adapted to be moved upon their respective pivotal axes to carry the rack to and from a position within the case, and means to cause them to move on their separate axes in unison, said arm when in front position being movable with the turn-table about its axis. 70

2. In a display device, the combination of a case or cabinet, rack supporting arms carrying a rack and pivoted at and rotatable about separated centers near the front of the case to carry the rack to and from a position within the case, and when in front position movable about a common center to bodily rotate the rack for presenting all portions to the front of the case, and means connecting the supporting arms to cause them to move in unison on their separate centers. 75

3. In a display device, the combination of a case, a turn-table or rotatable support, rack supporting arms independent of and mounted on separate pivots carried by said turn-table or rotatable support, gearing connections between said arms, and means including a pin and locking recess, one on the turn-table and the other on one of said arms acting to lock said arms with the rack 80 in front position or in rear position. 85

4. In a display device, the combination of a case, a turn-table rotatably mounted in the case, a rack, arms independent of and pivotally mounted at diametrically opposite points on said turn-table and supporting the rack, connections between the arms to cause them to carry the rack bodily to and from a position within the case, means to restrain rotative movement of the turn-table, and means to restrain movement of the arms on their pivots. 95 100

5. In a display device, the combination of a case, a turn-table, a socket-plate connected to the case and in which the turn-table is seated for rotative movement, rack supporting arms pivoted eccentrically on said turn-table and transmitting the rack load to said turn-table, and means for limiting the pivotal movement of the rack supporting arms with relation to said turn-table. 110 115

6. In a display device, the combination of a case, a turn-table pivotally mounted in the case and supported for rotative movement only, rack supporting arms pivoted to said turn-table at diametrically separated points and also bodily rotatable with said turn-table, and means for bracing the pivotal mountings of the said arms to prevent 120 sagging thereof under load. 125

7. In a display device, the combination of a case, a turn-table mounted in the case, a rack, arms pivotally mounted at diametrically opposite points on said turn-table and 130

transmitting the load to the turn-table, and a yielding device mounted on one of said arms and engaging the turn-table to hold the arms with the rack in either front or rear position.

8. In a display device, the combination of a case, a turn-table mounted in the case, a rack, arms pivotally mounted at diametrically opposite points on said turn-table and carrying said rack, and a cap plate overlying

ing the adjacent ends of said arms and mounted on the turn-table.

In testimony whereof, I have signed my name to this specification, in the presence of two subscribing witnesses.

OSCAR L. SMITH.
